(12) **United States Design Patent** (10) **Patent No.:** **US D828,358 S**
(45) **Date of Patent:** **** Sep. 11, 2018**

(54) **SSD STORAGE DEVICE**

(71) Applicant: **SAMSUNG ELECTRONICS CO., LTD.**, Suwon-si (KR)

(72) Inventors: **G. M Lim**, Seoul (KR); **Eun-jin Yun**, Seoul (KR)

(73) Assignee: **SAMSUNG ELECTRONICS CO., LTD.**, Suwon-si (KR)

(**) Term: **15 Years**

(21) Appl. No.: **29/614,250**

(22) Filed: **Aug. 17, 2017**

(30) **Foreign Application Priority Data**

Feb. 17, 2017 (KR) 30-2017-0007660

(57) **CLAIM**

The ornamental design for an SSD storage device, as shown and described.

DESCRIPTION

FIG. 1 is a perspective view of an SSD storage device showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

Broken lines and unshaded portions contained within broken lines depict either features of the SSD storage device that form no part of the present design claim or exemplary elements that might be used in conjunction with the SSD storage device that are shown for illustrative purposes only and that form no part of the claimed design.
